UNITED STATES PATENT OFFICE.

CARL JOHN HAGSTROM, OF GLEN COVE, NEW YORK.

DOORLOCK.

Application filed September 10, 1924. Serial No. 736,862.

This invention relates to locking devices and has particular reference to French casement locks.

Among the objects of this invention is to provide a French casement lock adapted to be mounted upon a pair of co-operating doors or the like, one of said doors because it bears the weather strip or for other like reason, being adapted or intended to open first, said lock being so arranged that when the doors are closed, that section of the lock borne by the door that was the last to close will actuate a detent or the like within the section borne by the other door to prevent the unlocking of the door that was closed first before the other is again opened.

Another object of this invention is to provide a French casement lock so arranged that when the co-operating sections thereof are disengaged upon opening a door as by withdrawing said means borne by the section mounted upon the opened door from a socket or the like provided within the other section, said detent enters and closes said socket which in the present state of the art is left open so that not only is a person and particularly a child prevented from inserting his finger thereinto and clamping or injuring the same by turning the knob, and from tampering with the lock, but likewise the appearance of the lock is greatly improved.

With the foregoing and other objects in view the invention consists in the arrangement and combination of parts hereinafter described and claimed, and while the invention is not restricted to the exact details of construction suggested or disclosed herein, still for the purpose of illustrating a practical embodiment thereof reference is had to the accompanying drawings, in which like reference characters designate the same parts in the several views, and in which—

Figure 1 is a perspective view of the lock showing movement toward engaging position.

Fig. 2 is an inside elevation with a part removed about on the line 2—2 of Fig. 3.

Fig. 3 is a partial plan section on the line 3—3 of Fig. 2.

Fig. 4 is a view of the mechanism with the left half of Fig. 2 in unlocked position.

Fig. 5 is a perspective view of the detent.

Referring now more specifically to the drawings, A and B represent the usual parts or sections of a French casement lock which are mortised at the meeting edges of a pair

of co-operating doors or the like. The section A is mounted upon the door which is closed last by a swing toward the other previously closed door as indicated by the arrow a. The sections are provided with the usual engaging angular portions 10 and 11, the former having an offset 12 while the latter has a recess 13 to receive the same, said offset having a socket to receive the usual chamfered snap bolt 14. Suitable bolts 15 and 16 or the like, shown here as broken off, co-operate with suitable keepers in a frame above and below the doors. Knobs or handles are fastened to B at 17 preferably only upon the inner side of the door whereby the bolts 16 can be operated to unlock the door. Knobs or the like are secured to A at 18 preferably upon both sides of the door to operate the bolts 14 and 15, suitable key operated means being provided at 19 whereby the mechanism can be locked against operation at 18 after the door bearing section A has likewise been locked shut. Since it is obviously undesirable to have the bolts 16 retracted before the A door has been opened, mechanism comprising a detent 20 or the like has been provided so arranged as to fulfill the various objects herein set forth.

The detent 20 which is preferably somewhat larger than the bolt 14 is mounted slidably within a socket 21 which opens centrally upon the recess 13 and into which the bolt 14 is adapted to snap when the doors are closed as will soon be described. The detent has a chamfered face 22 which slopes oppositely to that of the bolt 14 whereby the actuation thereof for sliding movement within the socket aforesaid by means of the edge of the offset 12 when the sections A and B engage is facilitated. Thus as can be seen readily from Fig. 1, when section A moves into engagement with B, the offset 12 will ride along the chamfered face of the detent so that when the offset has entered the recess 13, the detent will have been fully depressed into the socket 21, leaving a space within said socket adjacent the chamfered face for reception of the bolt 14.

The detent comprises a guide or tongue 23 formed preferably at the base of the triangular portion of the detent and extending parallel thereto and rearwardly of the chamfered face so as to co-operate with the track or guideway 24 which is formed within the offset portion 25 of the casing

25 so as to guide the detent in its reciprocation between the extreme inward limit of motion as shown in Figs. 2 and 3 and the extreme outward limit of motion as shown in Figs. 1 and 4. Secured to the base of the detent is a screw or headed pin 26 which is adapted to ride in the slot 27 formed lengthwise of the guideway 24, the head engaging the wall about the slot so as to retain the detent within the guideway. A shoulder or the like can be formed at 28 into which is set a pin 29 which is adapted to bear upon the inner face of the flange 11' (see Fig. 4) to limit the outward movement of the detent against the force of a spring 30 which bears in a notch or guideway 30' formed at the rear of the head of the detent and adjacent to the guide 23.

The bolts 16 are operated in any usual manner as by the tumbler 31 which actuates the lever 32 which in turn causes the bell crank 33 to operate against the force of the spring 34 to retract the bolts, said spring tending to cause the bolts to be projected. When, as has previously been stated, the doors are locked shut, it is undesirable to have the section B operable for unlocking before the door A has first been unlocked and opened. This is one of the functions which as will now be seen is accomplished by the detent 20. For the locks being properly engaged as shown in Figs. 2 and 3, and the bolts 16 snapped outwardly into their keepers, the detent under actuation by the edge of the offset 12 will have moved inwardly between the ends of the bolts 16 so as to lie in their path as shown in dot and dash lines in Fig. 3, and so preventing the retraction thereof by actuation of the mechanism at 17. This section can not therefore be unlocked before the door A has been opened, when the detent 20 will be moved outward by the spring 30 into position shown in Figs. 1 and 4, permitting the bolts 16 to be retracted, the ends thereof then sliding inward and behind the detent 20. This function which is performed by the detent 20 is in the present state of the art taken care of by the bolt 14. By adding the detent 20, however, I secure the important advantage of having a closure for the socket 21 preventing tampering with the lock when the door A is open, or the insertion of a finger as by a child and the clamping thereof between the bolts 16 when the mechanism is actuated by a turn of the knob at 17. Furthermore, the appearance and salability of the lock is greatly improved thereby.

60 I claim:

1. In a French casement lock, the com-

bination with a section having engaging means including a bolt and a section having a socket to receive the bolt, of a detent adapted to move within said socket and to project therefrom so as to close the same when the lock is unlocked, said engaging means serving to engage the detent to slide the same inward from the socket into its section when the sections engage so as to permit reception of the bolt within said socket, said detent having a chamfered end to facilitate actuation thereof.

2. In a French casement lock, the combination with a section having a bolt and a section having a socket to receive the same, of a detent adapted to move within said socket and to project therefrom so as to close the same when the lock is unlocked, said detent being slidable from the socket into its section by the other section when the sections engage so as to permit reception of the bolt within said socket, said bolt and said detent being chamfered in opposite directions.

3. In a French casement lock, the combination with a section having a bolt and a section having a socket to receive the same, of a detent adapted to move within said socket and to project therefrom so as to close the same when the lock is unlocked and is adapted to be projected into its section to permit the reception of the bolt within said socket when the sections are engaged, the section having the socket being provided with a bolt and the detent being adapted to lock the same against operation when said detent has been actuated inwardly.

4. In a French casement lock, the combination with a section having a bolt and a section having a socket to receive the same, of a detent adapted to move within said socket and to project therefrom so as to close the same when the lock is unlocked and adapted to be projected into its section to permit the reception of the bolt within said socket when the sections are engaged, the section having the socket being provided with a slot and the detent being provided with means to slidably engage the same.

5. In a lock, the combination of a section having an integral extending portion upon the face thereof, a co-operating section having a detent projecting therefrom and actuatable by said integral extending portion to be projected into its section of the lock, and a bolt having cooperation with said detent, said bolt being arranged to be locked by said detent when the same is projected as aforesaid.

In testimony whereof I affix my signature.

CARL JOHN HAGSTROM.
